TICKET FOR STREET-CARS AND SIMILAR USES.

1,072,627.

Specification of Letters Patent. Patented Sept. 9, 1913.

Application filed January 25, 1913. Serial No. 744,159.

To all whom it may concern:

Be it known that I, LOUIS P. LIPPS, a citizen of the United States, residing at Cleveland, in the county of Cuyahoga and State 5 of Ohio, have invented a new and useful Ticket for Street-Car and Similar Uses, as to which I hereby declare the following to be a full, clear, and exact description, reference being had to the drawings that action 10 company and make a part of the specification, wherein the same parts are designated by the same letters throughout the figures.

The idea in question essentially involves the production and use, as a unitary article, 15 of a series of tickets, detachably connected together, to each member of which series is similarly joined a subordinate ticket or coupon that may be used for the procurement of some further privilege, or service, of the 20 same or kindred nature as that to which the main ticket relates, and, at a denominational value that is proportional to and divisible into that of the principal ticket. While adaptable equally to many 25 other conditions of passenger traffic generally, where a difference in accommodation is to be reconciled by a difference in fare, as where first and second-class cars are used in the same train, different grades of compartments or seats in the same car, or extra 30 privileges or a varied quality of service is offered in any situation in exchange for the coupons referred to, its widest application will be to the system of transfer, from one 35 line of street-cars to another, that prevails in most cities. In these systems, the privilege of changing over to and finishing their ride on a connecting line, is given to passengers who have paid one fare, upon the 40 payment of a small extra charge of one cent or more, the conductor who has received the main ticket or fare handing the rider, as the evidence of his right to transfer to another car, a transfer-slip upon which he punches 45 or stamps the hour and date of the transaction. This transfer, however, must be used within a certain time limit or it becomes invalid, and when given up to and received by the conductor on the car to which transfer 50 is made, it is turned in and accounted for with all the formalities of regular or principal tickets. As thus practiced, the system, in the operations of a single company, may involve the collecting and han-

dling by conductors of many millions of 55 minor coin-pieces annually, and necessitate a corresponding amount of petty details in every department of the service, which, besides the cost involved, are a frequent source of annoyance to the traveling public, and of 60 delays and interferences with the scheduled running of cars and the operations connected therewith.

The slip used, in most cases, is of thin 65 paper and of dimensions that make it inconvenient for the passenger to carry without folding, and, in consequence, it is often surrendered in the shape of a crumpled or irregular package which must be hurriedly straightened out by the conductor upon its 70 receipt, with the result of distracting his attention from more important duties during the process, and sometimes of tearing or mutilating the slip itself. So too the universal use of such strips involves a not in- 75 considerable expense and original loss to the operating company, by reason of the fact that the marginal dates and numbers thereon require, at least, three several and special punchings for and preliminary to each day's 80 issue. The strips must be fitted thus for each day of the year in estimated quantities, that, out of precaution, are naturally well above any low and conservative estimate. Inasmuch as any unused issue for one day 85 cannot be repunched and issued for another, it follows that there is a constant overissue and daily waste of unused slips on this account, that is soon measured by noticeable 90 figures.

It is sought to avoid undesirable features of the prevailing system of transfers by the present invention, not only by the substitution of the coupon system for the transfer-slips as now used, but by arranging purchasable sheets of tickets, with detachable coupons, carrying the right to transfer, in such units that the face value of the coupons will always be aliquot parts of the main fare and therefore utilizable for both fares and transfers. 95

In the drawings Figure 1 represents a set of two units of tickets and coupons where the denominational values are respectively three and one. Figs. 2 and 3 are single 105 units of the sort where the denominational values are severally 4 and 5 to 1, and Fig. 4 represents one of the coupons as it may be

stamped so as to take the place of and answer as the transfer-slip in present use.

As will be observed the several units portrayed are rectangular sheets of thin cardboard, divided into ticket spaces by transverse scores or perforations indicated by the dotted lines. The spaces are themselves cut by a similar score or weakened line that extends at right angles to the same at a unit 10 form distance from the side of the sheet. The latter is thus divided up into the desired number of detachable tickets d , d' , d'' , to serve as the initial or main fare, and the smaller tickets, or coupons e , at the ends of 15 the said tickets, to serve in place of the cent or other coin that is now handed in as the price of a transfer.

When the denominational or face value of the subordinate ticket or coupon, is an 20 aliquot part or factor of the value of the main ticket, by having as many tickets (and corresponding coupons) in a sheet as the number of times the face value of a coupon is contained in that of the main ticket, or a 25 multiple thereof, the coupons may always be broken up and used, if desired, as the tickets themselves, without leaving odd coupons with an aggregate value that is less than the main fare. Also, in case there is an odd 30 number of coupons at any time, whether stamped or not for a definite transfer trip, these will always be available to be handed in, with other coupons, in discharge of a main fare. By the possibilities of an arrangement of this kind, ticket-sheets, with 35 transfer coupons attached as described, may be the only form in which tickets are issued, and they may be sold to passengers indifferently without regard to whether they are 40 to be used in connection with transfers, or only for uninterrupted rides. If the denomination of the principal ticket is three cents, for instance, and of the transfer one cent, the card or sheet of tickets should contain 45 either three main tickets, and corresponding coupons, or six, nine, etc. If such values are respectively four and two cents, the set should be made up of two, four, six, eight, etc. tickets, and so on, in similar cases. 50 The adoption of this plan will accordingly reduce the transactions connected with the privilege of street-car transfers to a minimum, since it will merge the same, for the most part, in the purchase of the principal 55 tickets to which such right is incident, do away with the need of supplying transfer

coins each day to conductors, and, the expensive and sometimes wasteful process of preparing a special supply of transfers for each day of the year, which cannot be re-adapted and used for any other day. 60

An appreciable advantage and gain, from such adoption, will be realized by the car-riders themselves, in the fact that, unlike the transfer slips now issued, the coupon 65 will be good toward a main fare, even though it has been punched for a transfer, but, for any reason, has not been offered and used for such purpose: Now, if the time limit punched on the transfer slip has expired, or it is not used for the transfer ride intended, it has no value at all and the amount paid for the same is a total loss. 70

Obviously the coupons e , may be given suitable dimensions to be punched or 75 stamped as is indicated in Fig. 4.

It should be plain from the context, as well as the language of the claims herewith, that the invention is not supposed to comprise any manufacture except in original 80 sheets of as many as two pairs of the tickets and coupons described.

Having thus described my invention, what I claim as new and wish to secure by Letters Patents is:—

1. As an article of manufacture, a series of detachably connected tickets and coupons bearing indicia representing denominational values thereon, the values on the tickets being severally divisible by the values on 90 the coupons in each case, and, the number of members of said series being equal to the number of times the indicative value on a coupon is contained in the indicative value on the ticket to which such coupon is attached, or in a multiple of said last named value, substantially as shown and described. 95

2. A sheet of detachably connected tickets and coupons bearing indicia thereon, representing denominational values, which are 100 evenly divisible one by the other, the number of said tickets and coupons in a sheet, corresponding with the number of times the indicative value on the one is contained in the indicative value of the other or in a 105 multiple of the latter value, substantially as shown and described.

LOUIS P. LIPPS.
